PORTABLE ANTENNA MAST

Clarence S. Badertscher and Hugh G. Austin, Wooster, Ohio, assignors to Thomas Mold & Die Co., Wooster, Ohio, a corporation of Ohio

Application July 23, 1949, Serial No. 106,473

2 Claims. (Cl. 189—26)

This invention relates broadly to telescopic masts, the exemplary embodiment illustrated herein being adapted for the support of a television antenna.

In certain localities such as the valleys in mountainous or rolling country it is difficult to obtain satisfactory video reception unless the antenna is relatively high, say fifty to one hundred and fifty feet. The erection of a rigid mast of such length is hazardous and frequently impossible in urban districts when the working area is limited. The present invention contemplates a mast which may be readily erected on the roof of a multistory building without encroachment on the adjacent property, a mast that may be lowered with ease and dispatch when it is necessary or desirable to alter the antenna carried thereby, a mast in which the telescopic sections are positively locked in their distended position, and a mast which will eliminate the arduous work of delivery, the excessive cost of installation, and the hazards attendant the raising and lowering of a pole of unitary structure.

In addition to the foregoing objects and advantages, the invention further contemplates a mast which is light in weight, rigid of structure, economic of manufacture, and a mast which is safe, durable, and efficient.

Other objects and advantages more or less ancillary to the foregoing, and the manner in which all the various objects are realized, will appear in the following description, which, considered in connection with the accompanying drawings, sets forth the preferred embodiment of the invention.

In the drawings

Fig. 1 is a vertical section of the mast, the upper portion thereof being shown in elevation;

Fig. 2 is a sectional view shown upon an enlarged scale of the upper end of one of the tube sections;

Fig. 3 is an elevational view of the mast illustrating the position of the parts incident the initial step of installation;

Fig. 4 is a sectional view of the valve structure embodied in the improved mast; and

Fig. 5 is an end elevational view of the base plate.

Referring first to Fig. 1, the mast assembly comprises a base plate 10, a second plate 11 hinged upon the upper face thereof, a tubular member 12, welded or otherwise secured to the upper plate 11, and cap screws 13 mounted in the plate 11 and threaded in the base 10 for the securing of the two plates in interlocked relation. The hinge structure preferably comprises a pair of apertured lugs 14 disposed in spaced relation with each other on the upper face of the plate 10, a hinge pin 15 mounted therein, and a pair of similar lugs 16 affixed upon the plate 11 in contiguous relation to the lugs 14. The plate 10 as illustrated is provided with spurs or anchor pins 17 designed to restrain lateral movement of the plate relative to the ground or other supporting surface during and subsequent the erection of the mast.

The mast comprises a number of sections formed by a plurality of tubular members T progressively reduced in diameter and disposed in telescopic engagement. The

2

number of sections in each assembly depends upon the over-all height or altitude required for the antenna, and the diameter of the tubular members depends upon the number of sections required. It has been found that satisfactory results may be obtained in a seventy foot mast by using four twenty foot sections, the lowermost member being two and one-half inches in diameter and the members of remaining sections each approximately one-half inch smaller. The lower section 18 is welded or otherwise

affixed to the tube or receptacle 12 which is provided with a conduit fitting comprising a valve 19 to facilitate the attachment of a conduit leading to a portable hydraulic pump (not shown) or other source of fluid under pressure. The upper end of the tubular member 18 is provided with a cap 20 mounted in fluid-tight relation thereon and formed with a bore therein to accommodate the sliding movement of the second tube section 21. The lower end of the member 21 is sealed with a cap 22 having a tapped opening therein for the reception of a cap screw 23 to accommodate the retention of a cup washer 24 and backing plate 25. The cap 22 is further drilled and tapped to support a valve cage 26 which, as illustrated in Fig. 4, comprises a spring-pressed poppet valve 27 seated in a passageway 28 leading from the interior of the tube 18 through a cross bore 29 and opening 30 to the interior of the tube 21. The valve cage is further provided with a passage 31 leading from the tube 18 through the bore 29 and opening 30 to the interior of the tube 21. The passage 31 is formed with a shoulder 32 therein defining a valve seat for a ball check valve 33 retained in the passage by a pin 34 adjacent the throat of the opening.

The member 21 is further provided with a stop collar or shoulder piece 35 welded or otherwise affixed from the outer wall thereof at a point which will afford a bearing of requisite length to support the structure when the tube is in its distended position. The collar not only arrests the outward movement of the member when brought into engagement with the cap 20 during the elevation of the mast, but also provides a shoulder for the engagement of a snap latch 36 mounted upon the upper end of the member 18. The latch (Fig. 2) embodies a carrier 37 secured to the cap 20, a plunger 38 therein formed with a beveled face 39, a spring normally urging the plunger inwardly towards the tube 21, and a bell crank 41 pivotally mounted in the cage with the upper arm 42 thereof engaged within a slot 43 in the lower face of the plunger. The free end of the bell crank protrudes beyond the outer end of the carrier 37 and is preferably formed with a shouldered end portion 44 to accommodate the use of a gaff or pull rod during the retraction of the member sections.

The caps, valves, and latches for the member sections 45 and 46, as shown in Fig. 1, are of identical construction, save as to size, as those heretofore described in connection with the tubes 18 and 21. The cap on the free end of the top section may be suitably drilled for the support of an antenna post 47, a cross arm, or should the mast be used as a flag pole, a journal bearing for the support of a sheave spindle. The cups are formed with eyelets 48 disposed in equi-spaced relation about the circumferential edge thereof for the retention of guy wires 49 which may be anchored, adjusted, and tightened during or subsequent the erection of the mast.

When the mast is installed, the assembly is laid upon the ground, roof, or other surface with the base plate 10 folded out in parallel relation to the medial axes thereof (Fig. 3). The plate is next anchored to the supporting surface with the pins 17 or bolts secured in place. The assembly is then rocked to a vertical position and locked by the screws 13 and guy wires 49. A hydraulic pump is next connected to the fitting 19 and a fluid, preferably oil, is pumped into the tube 18, thus causing the tube section 18 to travel upward. When the stop collar 35 engages

the cap 20, the fluid pressure in the cylinder will overcome the spring load imposed upon the poppet valve 27 and permit the fluid to pass into the chamber defined by the section 21. The remaining sections of the assembly are elevated in a similar manner. As the sections ascend the latch plungers 38 will be forced outwardly until the collars 35 have passed thereover. As soon as the collars clear the plungers the springs 39 will effect the return thereof, thus locking the sections in their elevated position. When all of the sections are fully extended, the valve 19 may be closed and the pump removed. When the fluid pressure in the tube sections is relieved and the valve 19 is reopened, the balls in the check valves 33 will fall and facilitate the drainage of the oil from the assembly.

According to the preferred mode of operation the hydraulic fluid is removed from the interior of the mast after all of the sections are locked into their fully extended positions. Thus the valve 19 may simply be opened to allow the hydraulic fluid to drain from the mast. There is, of course, no objection to allowing the fluid to remain in the mast in certain specific situations, but such a mode of operation does not fully utilize the advantages and benefits of the invention.

The mast may be lowered after the hydraulic fluid is removed from the mast by means of suitable ropes or cables which are attached to the arms 41 of the latch means. Alternatively, of course, where access might be readily had to the upper end of the bottom section 18 and the remaining sections are of approximately the same length as the bottom section the successive sections may be lowered by tripping the latch arms 41 in turn.

Although the foregoing description is necessarily of a detailed character, in order that the invention may be completely set forth, it is to be understood that the specific terminology is not intended to be restrictive or confining, that the invention may be employed in environs other than the television antenna mast referred to above, and that various rearrangements of parts and modifications of detail may be resorted to without departing from the scope or spirit of the invention as herein claimed.

We claim:

1. A mast for radio antenna comprising, in combination, a base section, a plurality of middle sections and a top section, the said sections comprising a plurality of tubular members, each nested within another inwardly from the base section for extension from the base section in the order of their height on the mast, the base section and the middle sections each having an annular inwardly-extending member attached at the top end thereof with each said member abutting the exterior of the tubular member of the next section inwardly thereof for guiding each next inward section, the middle sections and the top section each having a shoulder piece attached adjacent the bottom thereof with each of said shoulder pieces projecting outwardly from the exterior of the tubular member of the section to which it is attached for engaging the annular

member of the next outward section and limiting the upward travel of the inward section to which it is attached, and fluid sealing means attached to the lower end of each of the middle sections and of the top section below the shoulder piece thereof and in fluid-tight engagement with the inside of the tubular member of the next section outward to confine hydraulic fluid to the portion of the outward section below the lower end of the inward section, means closing the top section against fluid flow there-through, a fitting at the lower end of the base section for admitting hydraulic fluid to lift the sections to an extended position, a latch member at the upper end of the base section and of each of the middle sections arranged to move in and out of the outward section to engage and disengage the lower side of the shoulder piece of the companion inward section for holding the said companion section in an extended position with respect to the outward section so that the hydraulic fluid may be removed from the mast, a latch carrier supported by each outward section and spring means between the carrier and the latch member for holding the latch member in said engaged position, and means for releasing said holding action of said spring means on the latch member to lower the mast comprising an outwardly extending arm at the upper end of the base section and of each of the middle sections operatively engaged with the latch member and a pivoted support for the arm on the latch carrier whereby the latch members may be successively unlocked to permit the sections to drop into a collapsed position.

2. The mast defined in claim 1 in which a member is attached to the bottom end of each of the middle sections and of the top section for closing those sections, and in which there are valve means providing fluid communication through the said members closing said sections including a spring-loaded, normally closed valve arranged to be opened by fluid in the next section outward thereof and a normally open valve arranged to be closed by pressure of fluid in the outward section.
